UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed December 1, 1922. Serial No. 604,196.

To all whom it may concern:

Be it known that I, HENRY W. O'NEILL, a citizen of the United States, residing at Brooklyn, in the county of Kings, State of New York, have invented certain new and useful Improvements in Telephone Systems, of which the following is a full, clear, concise, and exact description.

This invention relates to telephone systems and more particularly to signaling arrangements employed therein.

It is an object of this invention to automatically select signaling currents of different frequencies as required for controlling signals over different circuits.

It is a further object of this invention to automatically select signaling currents of different frequencies to selectively signal different stations on a transmission line.

An additional object of the invention is to provide an improved arrangement for enabling an operator to control the character of a signal displayed at a distant point.

A further additional object of this invention is to provide that an originating operator may control the signals at successive distant switching points during the building up of a so-called "through" connection which control also includes the manipulation of the signal at the called station to indicate that the call was extended over a long distance or toll line.

A still further object of this invention is to provide that on a built-up connection, an originating operator may so control the character of the signals displayed at each switching point as to indicate whether the attention of operators at such points is required, and also to operate all of such signals simultaneously to indicate at the switching points that the connection may be taken down.

A further additional feature of this invention is to provide an improved system for signaling over a number of types of telephone circuits without the use of composite ringers.

The foregoing and other objects of this invention are attained by the provision in a link circuit of switching means, the operation of which is dependent upon the characteristics of the line terminals with which the link cooperates in establishing a connection. The position of the switching means determines the frequency of the signaling

currents available for use on a connection. After the connection is established, the operator may cause a signal at a distant station to light steadily or intermittently, under control of a ringing key. If the key is actuated for a prolonged interval an interrupter is connected in series with the signaling current to the line, but if the ringing key is actuated momentarily the signaling current is applied steadily to the link circuit independently of the interrupter.

The invention will be readily understood from the following detailed description and by reference to the accompanying drawings in which Fig. 1 shows a universal cord circuit adapted to cooperate directly with a subscriber's line or indirectly therewith through a toll switching trunk in establishing a telephonic connection. Fig. 2 shows the terminals of three toll lines adapted to be connected individually either directly or indirectly with a subscriber's line through the universal cord circuit shown in Fig. 1.

In order to describe the invention in detail a toll call originating at station A, Fig. 1, will be traced through to the toll switchboard position B, Fig. 2. In accordance with the well known practice, it may be assumed that a ticket covering the details of a call originating at station A has reached the toll line operator at a position at which cord circuit C is located. Over an order wire circuit, not shown, the operator then requests connection with station A from a toll switching operator who assigns the trunk T and inserts plug 10 into jack 11. Following this the line operator inserts plug 12, associated with the cord circuit C, into the jack 13 of the assigned toll switching trunk T.

When a toll switching operator inserts plug 10 in jack 11, a circuit is established which may be traced from grounded battery, through the winding of relay 20, sleeve contacts of plug 10 and jack 11, and thence to ground through the winding of cut-off relay 21. Relay 20 operates and, at its inner armature and back contact, disconnects the busy test lead BT from the tip conductor of the trunk T and, at its front contact, renders the tip conductor of the trunk continuous. At its outer armature and front contact, relay 20 establishes a circuit for supervisory lamp 22 which may be traced from grounded battery, through

lamp 22, outer armature and front contact of relay 20, resistance element 23, back contact and armature of relay 24 to ground.

The lamp 22 is illuminated in this circuit.

5 The line operator, upon inserting plug 12 into jack 13 effects the energization of relay 24 over two circuits, one of which may be traced from grounded battery, left-hand winding of relay 24, conductor 29, inner 10 break contacts of relay 30, conductor 31, upper right-hand winding of repeating coil 32, tip contacts of jack 13 and plug 12, upper normal contacts of key 33 and thence to ground through the upper left-hand 15 winding of repeating coil 34; the other circuit may be traced from grounded battery, winding of relay 35, conductor 36, lower left-hand winding of repeating coil 34, lower normal contacts of key 33, ring contacts of 20 plug 12 and jack 13, lower right-hand winding of repeating coil 32, conductor 37, outer break contacts of relay 30, conductor 38, and thence to ground through the right-hand winding of relay 24.

25 Relay 24, in operating, interrupts the circuit for guard lamp 22 which is thereupon extinguished to notify the originating toll switching operator that the line operator has seized the proper trunk T in establishing 30 the connection. In case the toll line operator, through error or otherwise, had failed to take the assigned trunk T, relay 24 would have remained inert and the continued glow 35 of the lamp 22 would thus have indicated this irregularity to the toll switching operator.

It is to be noted that upon the insertion 40 of plug 12 into jack 13, relays 26 and 25 do not operate owing to the high resistance element 27 associated with the sleeve of jack 13. Lamp 28 will nevertheless, due to the immediate operation of relay 35, be lighted 45 over the following circuit: battery, lamp 28, armature and back contact of relay 26, armature and front contact of relay 35 to ground. The glowing of lamp 28 indicates 50 to the line operator that the connection has been made at the distant end of the trunk circuit and that ringing may be proceeded with. If now key 33 is actuated, the main conductors of the plug 12 are transferred 55 from the right-hand portion of the cord circuit C by way of the right-hand armature and back contacts of relay 25 to sources of alternating currents 57 and 58. Currents 60 from these sources may now traverse the main conductors of the trunk circuit T, right-hand windings of the repeating coil 32, thence to conductors 31 and 37, 72 and 73, 65 and through a circuit completed through an associated condenser and the windings of relay 59. This relay 59 may be of any suitable alternating current type, but preferably of the type disclosed in the copending 70 application of H. W. O'Neill, Serial No.

526,152, filed December 31, 1921. Under the influence of these incoming alternating currents, the normally closed contacts 60 of this relay 59 separate, and open the obvious circuit normally holding the relay 43 70 energized, causing this relay to release. Relay 43, in releasing, disconnects the right-hand portion of the trunk circuit equipment, and applies ringing current from a source 61 by way of the main conductors 75 of the plug 10 and jack 11 to the line of station A. It is pointed out that current from the battery and ground connections at the relay 24 retain this relay operated 80 due to the loop path through the sources of alternating currents 57 and 58 during the ringing period. To prevent the extinguishing 85 of lamp 28 during this period, whenever such an arrangement is desirable, relay 35 may be maintained energized by closing a circuit therefor to ground through the make-before-break contacts 90 of key 33. The maintenance of relay 24 operated thus avoids lighting the lamp 22 at this time. The sources 57 and 58 supply current at 90 respectively different frequencies as required for operations, to be described hereinafter. In connection with the signaling of the station A, currents of a single frequency may be sufficient to operate relay 59, 95 although this relay may be of a universal type relative to control through a wide range of frequencies, and therefore respond to the joint effect of the sources 57 and 58.

On cessation of the ringing current from 100 cord circuit C the resulting restoration of relay 59 and the reoperation of relay 43 disconnects the ringing current from line leading to station A and re-establishes the 105 continuity of the conductors of the trunk. When the subscriber at A removes his receiver from the hook, this re-establishing of trunk conductors permits a circuit to be traced from grounded battery, through resistance 41, winding of supervisory relay 40, conductor 42, lower left-hand winding of 110 repeating coil 32 and thence over the ring conductors through plug 10 and jack 11, the apparatus at station A, returning over the tip conductor, upper left-hand winding of 115 repeating coil 32, and resistance element 44 to ground. Relay 40 in operating, completes a circuit from grounded battery through the right-hand winding of relay 30, 120 the left-hand winding of this relay to ground through the front contact and armature of relay 24. Relay 30 operates, switches the conductors 31 and 37 from relay 24 and joins them through a transmission 125 condenser 9. In this position of relay 30 the windings of relay 24 are, however, joined locally to continue the energization of the latter relay, while the windings of relay 59 are shunted by condenser 9. At the cord 130 circuit C the resulting cessation of direct

current through relay 35 over the trunk circuit permits its release and the extinguishment of lamp 28, such lamp having been, as hereinbefore explained, illuminated over 5 the circuit due to the previous operation of relay 35.

Assuming now that the plugs 10 and 12 are in their respective jacks 11 and 13, the line operator proceeds with the connection 10 and inserts plug 14 into jack 15, and in so doing causes the operation of the sleeve relays 47, 46 and 100 in an obvious circuit. Cut-off relay 100 in operating disconnects 15 the regular line relay 101 from the line and prevents its operation at this time. Relay

47 is marginal but the resistance of the cut-off relay 100 in series therewith is sufficiently low to permit relay 47 to operate. The operation of relay 46 performs no use- 20 ful function in this case as relay 47, in operating, prevents, by the attraction of its outer left-hand armature, the lighting of lamp 48, which therefore does not enter into the operation of the circuit at this time.

25 Relay 47 also in operating connects a 16 cycle current source 55 to its armatures and upon the actuation of ringing key 56, current from the source 55 flows over a path which may be traced through the armatures 30 and front contacts of relay 47, outer contacts of ringing key 56, tip and ring contacts of plug 14 and jack 15, line conductors 104 and 105, and then through the left-hand winding of relay 102 which bridges conductors 35 104 and 105. Relay 102 in operating establishes a circuit for lamp 109 which may be traced from grounded battery through the right-hand armature and back contact of relay 103, right-hand winding and contacts 40 of relay 102, and thence to ground through the filament of lamp 109. In response to this signal, the operator at position B may employ a cord circuit similar to cord circuit C in establishing a connection by way of a 45 toll switching trunk or otherwise to the called subscriber's station. Cut-off relay 103 in response to such connection releases relay 102 to extinguish lamp 109. The conversation between the subscriber at station 50 A and the called subscriber may now take place.

At the completion of the conversation, the subscriber at station A replaces the receiver on the switchhook and in so doing 55 interrupts the energizing circuit for relay 40, which relay retracts its armature thereby opening the energizing circuit for relay 30. Relay 30 in deenergizing re-establishes the energizing circuit for relay 35 which has been previously traced through relay 24. Relay 35 in operating re-establishes the circuit for lamp 28. Lamp 28 in lighting informs the line operator of the termination of the conversation.

60 The line operator then removes the plug

12 from jack 13 and, in so doing, causes the deenergization of relay 24, whereupon a circuit is established for lamp 22 from grounded battery, lamp 22, outer left-hand armature and front contact of relay 20, resistance element 23, back contact and armature of relay 24 to ground. Lamp 22 illuminates in this circuit and informs the toll switching operator that the period of conversation has ended and that the line operator has removed the plug 12 from jack 13. The operator then removes plug 10 from jack 11 thereby restoring the apparatus associated with the toll switching trunk T to normal.

To give a disconnect signal to the operator at position B, the line operator momentarily operates the ringing key 56 to apply low frequency ringing current from the source 55 over the line circuit. Assuming, as already mentioned, that a cord circuit similar to the cord circuit C is connected to jack 16 at position B, current will now flow through the relays in that cord circuit corresponding to relays 53, 68 and 54 of the cord circuit C, 90 but the relay corresponding to relay 68 only will be energized to illuminate a supervisory lamp corresponding to lamp 70. The operator at position B will then actuate the listening key 65 to ascertain whether the connection is to be disestablished. If now key 65 of the cord circuit at position B is operated, the holding circuit for the relay, corresponding to relay 68, is opened, causing the lamp, corresponding to lamp 70, to be extinguished. 100 The operator at position B may then disconnect the cord from the line circuit.

The line operator will then remove plug 14 from jack 15 whereupon the apparatus associated with the cord circuit C is restored 105 to normal.

It will now be assumed that a call originating at position B is intended for the subscriber at station D, the terminals of which are directly accessible to the line operator.

The line operator will in this case insert plug 12 into jack 75, the resistance of the sleeve of which is low. A circuit may then be traced from grounded battery, winding of relay 25, winding of relay 26, sleeve contacts of plug 12 and jack 75, and thence to ground through the winding of cut-off relay 76. The resistance of this circuit is low enough to permit the operation of marginal relays 25 and 26. The operation of relay 26 causes the lamp 28 to light over an obvious circuit.

The response of the subscriber at station D causes the operation of relay 35 over an obvious circuit and thereby extinguishes lamp 28. This lamp will again be lighted when relay 35 releases due to the restoration of the receiver to the switchhook at station D. The establishment of this connection therefore differs from that established to the sub- 125 130

scriber A only in that, upon the operation of ringing key 33, the 16-cycle current source 71 is connected directly with the subscriber's line D, due to the operation of relay 25, whereas in the previous instance, double frequency currents from the sources 57 and 58 were sent out over the toll switching trunk T, due to the non-operation of relay 25.

Having thus described the operation of the cord circuit C, first, when associated with a toll switching trunk having a high resistance sleeve terminal and a line requiring low frequency currents for signaling purposes, and second, when associated with a subscriber's line having a low resistance sleeve terminal and a line requiring low frequency currents for signaling purposes, the following description will be directed to the use of the cord circuit C when the outgoing end thereof is associated with the line E which has a high resistance sleeve terminal and which requires a double frequency current for signaling purposes.

To simplify the description, it will be assumed that the plugs 12 and 14 have been inserted in the jacks 75 and 110, respectively. The effect of inserting plug 12 into jack 75 has been described heretofore and need not be repeated in this connection.

Upon inserting plug 14 into jack 110, a circuit is established which may be traced from grounded battery, winding of marginal relay 47, winding of relay 46, sleeve contacts of plug 14 and jack 110, and thence to ground through the winding of cut-off relay 111. The resistance of the winding of cut-off relay 111 is sufficiently high to prevent the operation of relay 47 at this time. The operation of relay 46 effects in this instance, due to the non-operation of relay 47, the illumination of lamp 48 over a circuit extending from grounded battery, armature and front contact of relay 46, conductor 49, armature and back contact of relay 50, lamp 48, and thence to ground through the outer left-hand armature and back contact of relay 47 and the circuit controlling elements 51 and 52 associated with relays 53 and 54, respectively. Relay 111 energizes in series with relay 46 and at its left-hand armature and back contact disconnects the relays 112 and 113 from the line conductors of the line E.

The line operator then actuates ringing key 56, whereupon currents of 1300 and 1700 cycles from the sources 57 and 58, respectively, traverse a path extending from the sources 57 and 58 over conductors 80 and 81, armatures and back contacts of relay 47, contacts of ringing key 56, tip and ring contacts of plug 14 and jack 110, line conductors 118 and 119 of line E, and thence through the windings of relays 120 and 121 which are normally bridged across the line conductors 118 and 119. Relay 120 is tuned

to respond to 1300 cycle currents, whereas relay 121 will operate upon the application of 1700 cycle current to its windings.

It is to be noted that relay 122 is normally energized over a circuit which may be traced from grounded battery, thence in parallel through the circuit controlling elements 123 and 124 of relays 120 and 121, respectively, to the point 125, through the left-hand armature and front contact of relay 122, and thence to ground through the winding of relay 122 so that relays 120 and 121 in operating upon the application of current from the sources 57 and 58, respectively, to their windings interrupt this normally energizing circuit to effect the release of relay 122. Relay 122 thereupon retracts its armature which effects an obvious energizing circuit for lamp 126 located at position F.

In controlling the signal 126 to be steadily lighted, as above described, a single momentary operation only of the ringing key 56 is required. The present system provides that this signal may be intermittently energized through control from the cord circuit C. It is readily seen that succeeding momentary actuations of the key 56 will intermittently apply alternately currents from the sources 57 and 58 to effect the relays 120 and 121 to correspondingly cause the flashing of signal 126. Such flashing may be at a relatively slow rate, whereas the signal may be flashing at a distinctly different rate through an interrupter 85. In the actuation of ringing key 56, the uppermost contacts apply ground over an obvious circuit to energize a slow-to-operate relay 86. By retaining the key 56 operated for a sufficiently long period, the relay 86 will respond and open at its armature and back contact a path normally shunting this interrupter 85. In this case, the interrupter will intermittently apply currents from the sources 57 and 58 to relays 120 and 121 to correspondingly flash signal 126. Thus, the signal at the distant end of the line may be operated in a number of ways to suit various operating requirements as will hereinafter be described.

The operator at position F, upon noting the illumination of lamp 126, inserts a plug associated with her cord circuit into jack 127, whereupon cut-off relay 128 operates effecting an energizing circuit for relay 122, which may be traced from grounded battery, front contact and armature of relay 128, and thence to ground through the winding of relay 122. Relay 122, in operating, disconnects the line lamp 126. Relay 122, in operating, locks through its left-hand contacts to grounded battery at the normally closed contacts of relays 120 and 121 to prepare the circuit for receiving another call after the disestablishment of the present call. The

operated position of the talking key of the cord circuit C during the passing of the call to the operator at position F, closes a circuit from grounded battery, contacts of 5 relay 46, winding and right-hand normal contacts of relay 50 and the upper contacts of key 65 to ground. Following the initial response of relay 50, the lead to the ground at key 65 is disconnected while the right-hand forward contacts of relay 50 establish a self-locking circuit for relay 50 to ground through the normal contacts 51 and 52 of relays 53 and 54. This extinguishes the lamp 48.

15 Upon learning the details of the call, the operator at position F proceeds to complete the connection and signal the called subscriber, after which conversation may take place over the established circuit. It will 20 now be assumed that the calling subscriber has hung up and that the line operator has received a signal to that effect. In response to the disconnect signal the line operator removes plug 12 from jack 75. The line 25 operator thereupon actuates ringing key 56 whereupon 1300 and 1700 cycle currents from sources 57 and 58 are sent out over the line E. These currents operate relays similar to relays 53 and 54 of the cord 30 circuit similar to the cord circuit C which is connected to the line E at position F. Upon the actuation of relays 53 and 54, the holding circuit for relay 50 is opened thereby lighting lamp 48 steadily, which serves 35 as a disconnect signal at the position F.

Assuming that the operator at position F during the existence of the connection, desires to attract the attention of the line operator she will apply 1300 and 1700 cycle 40 current to the line E. Relays 53 and 54 of the cord circuit C respond to this current. The first impulse of current releases relay 50 to reconnect lamp 48. Succeeding impulses of alternating current, due to the 45 flashing of the ringing key or to the operation of a device similar to the interrupter 85 at position F, result in corresponding interruptions of the contacts of relays 53 and 54 and correspondingly disconnecting and 50 thereby flashing of the lamp 48, as relay 50 will be released upon the first interruption of contacts 51 and 52. The receipt of the flashing signal indicates to the line operator that her attention is desired by the 55 operator at position F. Operation of the talking key 65 in going in on the connection will result in the energization of relay 50 to disconnect lamp 48 in the manner previously described.

60 In some exchanges, there are lines terminating in a plurality of positions, some of said positions being accessible to attendants known as "inward operators, while other positions are accessible to attendants 65 known as "through" operators, and it is

often desirable that an originating line operator be able to reach either of these types of operators. Ordinarily, a call is initially answered at an inward operator's position. Following the receipt of a request for connection with an operator located at another type of position, the inward operator may join the toll line to an interoffice or inter-position trunk and thereupon herself signal the desired position or the answering 70 operator may depress a transfer key whereby a signal will be displayed at the desired position, at which point the toll line may be accessible on a multiple basis. However, important advantages may be secured by a provision, whereby an originating operator may directly signal or select any desired different type of position or point in a distant exchange, and in the system according to this invention, provisions for such service 80 have been made. With this end in view, the following description is directed to the establishment of a connection by means of the cord circuit C over the line L, the terminals of which are multiplied at one end 85 in jacks 130 and 131 and at the other end in jacks 132 and 133, the jack 130 being located at an inward operator's position and the jack 131 being located at a through operator's position.

Assuming that the plug 12 has been inserted in jack 75 and that the line operator desires to signal the inward operator, she inserts plug 14 into jack 132, whereupon a circuit is established extending from 90 grounded battery, through the windings of marginal relay 47 and relay 46, sleeve contacts of plug 14 and jack 132, and thence to ground through the right-hand winding of relay 135. Relay 135 in operating disconnects the line relays 136 and 137 from the line conductors 138 and 139 of line L. The right-hand winding of relay 135 is of such a resistance as to permit the operation of 95 relay 47 in series therewith.

The line operator then actuates ringing key 56, whereupon 16 cycle current from the source 55 flows out over the armatures and front contacts of relay 47, the front contacts of ringing key 56, tip and ring contacts of plug 14 and jack 132, line conductors 138 and 139, and thence through the windings of relay 140, right-hand winding of relay 141 and the outer armature and back contact of relay 142. Relay 140 is tuned to respond to current of a frequency of 1700 cycles, whereas relay 141 will operate upon the application of 16 cycle current to its winding. Relay 141 thereupon energizes and establishes a circuit which may be 115 traced from grounded battery, armature and front contact of relay 141, conductor 143, and thence to ground through the lamp 144. A locking circuit for relay 141 is also established extending from grounded battery, ar- 120

mature and front contact of relay 141, left-hand winding of relay 141, and thence to ground, through the inner back contact and inner armature of relay 142. The locking circuit just traced places relay 141 under the control of cut-off relay 142.

Upon noting the illumination of lamp 144, the inward operator inserts a plug associated with her cord into jack 130, whereupon the cut-off relay 142 becomes energized and interrupts the locking circuit for relay 141, whereupon the energizing circuit for lamp 144 is interrupted. Lamp 144 is thereupon extinguished and line relays 140 and 141 are disconnected from the line. The inward operator then connects her telephone set with the line and is informed by the line operator as to the details of the call, after which the line operator proceeds to complete the connection.

After conversation is completed and the receiver at station D has been restored to the switchhook, lamp 28 will light. The line operator noting this signal removes plug 12 from jack 75 and momentarily depresses ringing key 56 thereby applying ringing current from the source 55 over the line circuit L. A relay similar to relay 68 will then be actuated to light a lamp similar to lamp 70. Upon noting the illumination of this lamp the inward operator actuates her talking key which disconnects ground to release a relay similar to relay 68 which extinguishes the associated lamp.

If the line operator had signaled the through operator on line L, she would insert plug 14 into jack 133 whereupon a circuit is established extending from grounded battery, windings of relays 47 and 46, sleeve contacts of plug 14 and jack 133, and thence to ground through the right and left-hand windings of relay 135. Both windings of relay 135 being included in this series circuit, the resistance is sufficiently high to prevent the operation of relay 47. Relays 46 and 135, however, operate and perform the same function as described in the previous case. The line operator then actuates ringing key 56, whereupon double frequency currents of 1300 and 1700 cycles are intermittently connected through interrupter 85 to the tip and ring conductors of the line and traverse a path which may be traced over conductors 81 and 80, armatures and back contacts of relay 47, contacts of key 56, tip and ring contacts of plug 14 and jack 133, line conductors 138 and 139 of line L, and thence through the windings of relay 140 and the right-hand winding of relay 141 which are bridged across the line conductors 138 and 139. Relay 141 being tuned to operate only on 16 cycle current is not affected by the application of currents from the sources 57 and 58, whereas the 1700 cycle current from the source 58 effects the opera-

tion of relay 140, the 1300 cycle current from the source 57 being idly present at this time. Relay 140 thereupon operates and interrupts the normal energizing circuit for relay 145 which may be traced from grounded battery, 70 winding of relay 145, front contact and armature of relay 145, and thence to ground through the circuit controlling element 146 associated with the relay 140. Relay 145 is deenergized, retracts its armature and establishes an obvious circuit for lamp 147.

Upon noting the illumination of lamp 147, the "through" operator proceeds to answer the call by inserting a plug corresponding to plug 12, Fig. 1, into jack 131 which effects 80 the operation of cut-off relay 142 to extinguish lamp 147 by the operation of relay 145 from a ground supplied at the inner armature and front contact of relay 142. The "through" operator after having received the 85 details of the call from the line operator then proceeds to extend the connection to and signal the distant called office from which point the desired subscriber may be reached in the 90 well known manner.

Assuming that a cord circuit similar to the cord circuit C is provided at the through operator's position and at the distant called office, either of these operators may receive 95 a disconnect or a call signal.

The disconnect signal results from the momentary operation of ringing key 56 in applying the high frequency currents to the line circuit. In cord circuits at the distant points equipment corresponding to relays 53 and 54 100 will cause relays, such as 50, to release and energize signals, such as 48.

The call signal results from retaining the ringing key 56 operated for a certain interval 105 whereby the lamps corresponding to lamp 48 are flashed. It will be noted that with ringing key 56 actuated, a circuit is completed through the uppermost contacts of key 56 for slow-to-operate relay 86. This relay in operating removes the normally closed shunt path around the interrupter 85, thereby causing the frequencies from the sources 57 and 58 to be intermittently applied to the cord. As previously mentioned, this results 110 in flashing the lamps at the distant points. 115

After completion of conversation it will be obvious from the previous description how the connection may be released and the apparatus restored to normal.

What is claimed is:

1. In a telephone system, a link circuit adapted to interconnect lines of different characteristics, a bridge associated with said link circuit comprising a plurality of selectively responsive devices, a plurality of signals controlled thereby, and means dependent upon the characteristics of the line with which said link circuit is associated for selectively controlling said signals.

2. In a telephone system, the combina-

tion of a link circuit adapted to interconnect lines of different types, a plurality of signaling means, a relay dependent for its operation on the type of line associated with said link circuit for controlling some of said signaling means, and a bridge associated with said link circuit comprising a plurality of selectively responsive devices for controlling all of said signaling means, some of said devices operating independently of the operation of said relay to control the operation of some of said signaling means.

3. In a telephone system, a link circuit adapted to interconnect lines of different types, a plurality of signaling means, a plurality of current sources of different characteristics, a relay operative when said link circuit is associated with one type of line to connect one of said current sources to said link circuit and inoperative when said link circuit is associated with another type of line to supply said link circuit with current from another of said sources, a plurality of devices associated with one type of line responsive to currents of one characteristic to control a corresponding signaling means, and a plurality of other devices associated with another type of line selectively responsive to currents from corresponding sources to control said signaling means.

4. In a telephone system, a link circuit adapted to interconnect lines of different types, signaling means, a bridge associated with said link circuit comprising a plurality of selectively responsive electromagnetic devices, a plurality of current sources of different characteristics, and means dependent upon the type of line associated with said link circuit for selecting a current source to selectively actuate some of said electromagnetic devices whereby the operation of said signaling means is effected.

5. In a telephone system, a link circuit, a line, a plurality of operators' positions on said line, signaling means at each of said positions responsive to currents of different frequencies, and means associated with said link circuit automatically selected when the link circuit is connected to the line for selectively actuating said signaling means to signal the operator at one of said positions.

6. In a telephone system, a line, a link circuit, a plurality of operators' positions on said line, a bridge on said line including selectively responsive relays, a plurality of current sources of different characteristics associated with said link circuit, and means associated with said link circuit for automatically selecting and for connecting one of said current sources to said line to selectively actuate one of said relays to signal an operator at one of said positions responsive to the connection of said link circuit to said line at a corresponding operator's position.

7. In a telephone system, a link circuit, a

signal, sources of alternating currents, a manual switch in said link circuit, and means responsive to various actuations of said switch for variably connecting all of said sources of currents simultaneously to said link circuit to variably actuate said signal.

8. In a telephone system, a link circuit, a trunk circuit, a signal, sources of alternating currents, a key for said link circuit, means operative in response to a certain actuation of said key for applying current from all of said sources to said link and trunk circuits to actuate said signal in one manner, and means operative in response to another actuation of said key for applying current from all of said sources to said link and trunk circuits to actuate said signal in another manner.

9. A universal cord circuit comprising a relay at each end thereof, a plurality of current sources adapted to be controlled by either one of said relays so that a certain of said current sources is available for use when either one of said relays is in one position and so that other sources are available for use when either one of said relays is in the opposite position.

10. In a telephone system, a link circuit, a line adapted to be connected thereto, a signal associated with said line, a source of alternating current and a manual switch in said link circuit for connecting said source to the link circuit to operate the signal in a continuous manner, and means responsive to the operation of the switch for a certain period for connecting said source in an interrupted manner to the link circuit for a corresponding operation of the signal.

11. In a telephone system, a link circuit, a signal, a source of current, means for connecting said source of current to the link circuit comprising a key, a relay, and an interrupter, normally short-circuited by contacts of said relay, so arranged in a circuit that when the key is operated for a limited period the relay is not operated and the source of current is connected to the link circuit in a continuous manner, whereas if the key is operated a comparatively longer period the relay is operated and the interrupter thereby arranged to alternately connect the source to and disconnect it from the link circuit for a corresponding operation of the signal.

12. In a telephone system, a cord circuit, a trunk circuit, two signals associated with said trunk circuit, a plurality of sources of current in said cord circuit, means for connecting the cord circuit and the trunk circuit at two different points of the trunk circuit, means in said trunk circuit for making a source of current of one character available for operation of one signal in said

trunk circuit when the cord circuit is connected at one point to said trunk circuit and for making a source of current of a different character available for the operation of the 5 other signal in said trunk circuit when the cord circuit is connected to the other point of said trunk circuit, and means in said cord circuit for causing the operation of either one of said signals responsive to the 10 connection of the cord circuit to the corresponding point of the trunk circuit.

13. In a telephone system, subscribers' lines, a trunk circuit, a cord circuit adapted to be connected to either the trunk circuit

or a subscriber's line, sources of current in 15 said cord circuit, means for making a source of one character available for ringing purposes responsive to the connection of the cord circuit to the trunk circuit, and means for making a source of current of a different 20 character available for ringing purposes responsive to the connection of the cord circuit to a subscriber's line.

In witness whereof, I hereunto subscribe my name this 25th day of November A. D., 25 1922.

HENRY W. O'NEILL.
